UNITED STATES PATENT OFFICE.

JOSEPH LATOURELL, OF STERLING CENTER, MINNESOTA.

DRAFT-EQUALIZER.

SPECIFICATION forming part of Letters Patent No. 688,868, dated December 17, 1901.

Application filed June 20, 1901. Serial No. 65,313. (No model.)

To all whom it may concern:

Be it known that I, JOSEPH LATOURELL, a citizen of the United States, residing at Sterling Center, in the county of Blue Earth and 5 State of Minnesota, have invented a new and useful Draft-Equalizer, of which the following is a specification.

The invention relates to improvements in draft-equalizers.

10 The object of the present invention is to improve the construction of draft-equalizers and to provide a simple, inexpensive, and efficient one designed for use on mowers, binders, and the like and adapted to prevent the 15 side draft resulting from arranging three horses at one side of the pole and one horse at the other side.

The invention consists in the construction and novel combination and arrangement of 20 parts hereinafter fully described, illustrated in the accompanying drawings, and pointed out in the claims hereto appended.

In the drawings, Figure 1 is a plan view of 25 a draft-equalizer constructed in accordance with this invention. Fig. 2 is a transverse sectional view of the same. Fig. 3 is a detail perspective view of the connecting link or bar. Fig. 4 is a detail view of the keeper. Fig. 5 is a similar view of the clip-plate.

30 Like numerals of reference designate corresponding parts in all the figures of the drawings.

1 designates a doubletree pivoted at its center by a vertical bolt 2 to a laterally-extending bracket 3, which projects from one side 35 of a pole 4, as clearly illustrated in Fig. 2 of the accompanying drawings. The main whiffletree or doubletree 1 is provided at its ends with the ordinary doubletrees 5, to the terminals of which are connected singletrees 6. The inner end of the main whiffletree is located above the pole or draft-beam 4, and its singletrees are located at opposite sides of the same, and by arranging the said singletrees 40 as shown in Fig. 1 three of the horses or other draft-animals will be located at one side of the pole or tongue and one will be located at the other side.

The laterally-extending bracket is composed of upper and lower sides, and the upper side consists of inner and outer sections 45 7 and 8, which are pivoted together at their

adjacent ends by a rivet 9 or other suitable fastening device. The outer end of the outer section 8 is upwardly offset from the plane of 55 the upper face of the tongue or pole, and the lower section 9 of the laterally-extending bracket is curved upward and bent outward to arrange it beneath the outer end of the outer section 8, and it serves as a brace for 60 the same. The bracket is pivoted and is capable of a limited movement to avoid cramping the tongue or pole, and the pivot 2, which connects the main whiffletree to the bracket, also passes through the upper and lower sides 65 of a fork 10 of a rearwardly-extending transversely-disposed connecting-bar 11. The connecting-bar 11 extends across the tongue or pole and connects the main whiffletree with one end of a lever 12, which is fulcrumed at 70 its center on the tongue or pole by the pivot 13. The other end of the transverse lever 12 is connected by a link or rod 14 with a clip 15 of the tongue or pole. The fork 10 of the connecting bar or link 11 is formed by securing 75 a separate piece to the said bar or link 11, which is located at the upper face of the tongue or pole, and this separate piece is bent upward to offset its outer portion from the front end of the said link or bar 11. The 80 fork may be constructed in any other suitable manner, and the whiffletrees are located above the plane of the pole or tongue.

The pivot 13 of the transverse lever is preferably supported by a strap or brace 16, and 85 the ends of the lever, which are provided with hook-bolts 17, have perforations for the shanks of the hook-bolts. The hook-bolts are connected with the ends of the links 11 and 14 by rings or short links to form flexible connections. The rings 18, which connect the hook-bolts 17 with the bar 11 and the rod 14, may be of any desired number and of any form, and the link or bar 11 passes through a longitudinal keeper 19, secured to one side 90 of the tongue or pole and extending above the same and adapted to prevent the draft-animals from lifting the link or bar 11 when there is a strain on the traces or other connections.

100 The clip 15, which is located in advance of the whiffletrees, receives the tongue and is provided with a clip-plate 20, having an L-shaped arm 21 located at one side of the

tongue and extending outward horizontally from the same at a point midway between the upper and lower faces thereof to exert a central strain on the tongue and to prevent the same from being twisted. The said keeper 19 is provided at the lower terminals of its sides with extending lugs 22, engaging the lower face of the tongue.

The tendency of the tongue or pole to move laterally to the left is counteracted by means of the transverse lever and the connections between the main whiffletree and the pole or tongue. The link or rod, which is disposed longitudinally of the tongue or pole, at one side thereof, diverges rearwardly from the same, and any forward movement of the outer end of the pivoted bracket will pull forward on the left-hand end of the transverse lever and draw the right-hand end of the said lever rearward, and thereby move the tongue or pole laterally to the right. By this construction side draft is effectually prevented.

The inner or left-hand end of the main whiffletree is prevented from dropping upon the tongue or pole and engaging the pivoted bracket or the clip by means of a curved guard 23, consisting of a rod secured at its ends to the left-hand side of the tongue or pole and arched over the bracket and the clip.

It will be seen that the draft-equalizer is exceedingly simple and inexpensive in construction, that it is strong, durable, and adapted to be readily applied to mowers, binders, and the like, and that it is adapted to prevent side draft when three of the draft-animals are arranged at one side of the tongue or pole and one is located at the other side. The draft-equalizer prevents any twisting of the tongue or pole, and it will enable a machine to be turned with ease and without liability of cramping the neck-yoke.

What I claim is—

1. In a device of the class described, the combination with a tongue or pole, of a bracket extending from one side of the tongue or pole, a main whiffletree mounted on the bracket and provided with doubletrees and singletrees, said doubletree being connected directly to the ends of the main whiffletree, a transverse lever fulcrumed on the tongue or pole in rear of the main whiffletree, a longitudinal connection located at the same side of the pole or tongue as the said bracket and extending from the adjacent arm of the transverse lever to the adjacent side of the pole, and connections between the other arm of the transverse lever and the main whiffletree, substantially as described.
2. In a device of the class described, the combination with a tongue or pole, of a bracket pivoted to the tongue or pole at one side thereof, a main whiffletree mounted on the bracket and provided with doubletrees and singletrees, a transverse lever fulcrumed on the tongue or pole in rear of the main whiffletree, the transverse connections extending from the pivoted bracket across the tongue or pole to the farther end of the transverse lever, the longitudinal guide mounted on the tongue or pole and receiving the said transverse connections, and the longitudinal connection extending from the other end of the lever to the pole, substantially as described.

fletree, the transverse connections extending from the pivoted bracket across the tongue or pole to the farther end of the transverse lever, the longitudinal guide mounted on the tongue or pole and receiving the said transverse connections, and the longitudinal connection extending from the other end of the lever to the pole, substantially as described.

3. In a device of the class described, the combination with a tongue or pole, of a bracket extending from one side thereof, a main whiffletree mounted on the bracket and provided with doubletrees and singletrees, a clip secured to the tongue or pole in advance of the bracket and provided at one side with an arm extending laterally from the tongue or pole, between the upper and lower faces thereof, the diverging longitudinal connection extending rearward from the said arm, a transverse lever mounted on a pole in rear of the main whiffletree and having one of its arms secured to the said connection, and the transverse connection extending from the bracket to the other arm of the lever, substantially as described.

4. In a device of the class described, the combination with a tongue or pole, of the laterally-extending bracket pivoted to the tongue or pole, the main whiffletree mounted on the bracket and provided with doubletrees and singletrees, the transverse lever located in rear of the main whiffletree, the transverse connecting-bar extending across the tongue or pole and connected to one end of the said lever and provided at its front end with a fork receiving the main whiffletree, the clip located in advance of the bracket, the longitudinal rod secured to the clip and diverging from the tongue or pole and extending to the said lever, and the longitudinal guide mounted on the tongue or pole and receiving the transverse connecting-bar, substantially as described.

5. In a device of the class described, the combination with a tongue or pole, of a bracket extending from one side of the same, a main whiffletree mounted on the bracket and provided with doubletrees and singletrees, a lever located in rear of the main whiffletree and having one of its arms connected with the same, a clip mounted on the tongue or pole in advance of the main whiffletree, connections between the clip and the said lever, and the curved guard mounted on the tongue or pole and extending above the same and arranged to receive the main whiffletree to prevent the same from engaging the bracket or the clip, substantially as described.

In testimony that I claim the foregoing as my own I have hereto affixed my signature in the presence of two witnesses.

JOSEPH LATOURELL.
